UNITED STATES PATENT OFFICE

SAMUEL H. NUCKOLLS, OF STONE MOUNTAIN, GEORGIA, ASSIGNOR TO GEORGE FRANCIS WILLIS, OF ATLANTA, GEORGIA

PORTABLE ELECTRIC LAMP

Application filed April 26, 1930. Serial No. 447,630.

The invention relates to certain new and useful improvements in portable electric lamps adapted to be used either as an ordinary flash-light or as a pedestal lamp or lantern, to which end the lamp includes a casing provided with lateral openings adjacent the lamp socket to permit the lateral diffusion of the light, a sleeve associated with the casing to open and close the openings at will and a special arrangement of pivoted feet carried by the rear end cap and adapted to be swung out from the body to support the lamp or to be retracted within the peripheral lines of the cap, when not in use.

The invention is illustrated in the accompanying drawings, in which:—

Fig. 1 is a side view of the lamp with the lateral openings uncovered.

Fig. 2 is a partial view, corresponding to Fig. 1, showing the side openings covered by the sleeve. Fig. 3 is a section on line 3—3 of Fig. 1, with the feet in retracted position.

Fig. 4 is a similar view with the feet projected in supporting relation.

Fig. 5 is a section on line 5—5 of Fig. 4.

Fig. 6 is a partial longitudinal section on line 6—6 of Fig. 1.

Referring to the drawings, 1 indicates the tubular casing, which may be made of metal or any suitable plastic material and is provided at its opposite ends with the usual screw threads 4 and 15 by means of which the end caps are secured to the body portion. The forward portion of the casing between the end and the bulb socket and reflector is provided with lateral openings 2, by excising substantially rectangular sections of the casing, which leaves the extreme end section supported by the longitudinal ribs 3 between the openings 2.

The screw threaded end 4 of the casing is adapted to receive the cap or rim 5, which is provided with mating screw threads 6, and serves to lock the lens 7 in position against the outer end of the casing, as more particularly illustrated in Fig. 6. Secured within the casing to the rear of the lateral openings 2 is a block 10, in which is mount-

ed the usual lamp socket 11, which is surrounded by a reflector 12, the outer edge of which is substantially flush with the rearward edges of the openings 2, so that the lamp 13, when applied to the socket, will be in position to direct its rays laterally through the openings 2, when the latter are uncovered.

The openings 2 are controlled by a sleeve 8, which is in telescopic engagement with the outside of the body 1 and is provided at its forward end with a threaded flange 9 adapted to engage the screw threads 6 of the lens cap 5 and thereby lock the sleeve in closing relation with respect to the openings 2, so that the light will be directed through the lens in a forward direction only. When the sleeve 8 has been disengaged from the lens cap and retracted to uncover the openings 2, it will be apparent that the lamp may be used as a lantern or pedestal light to direct the light laterally, the rearward movement of the sleeve 8 being limited by a pin or stop 1' let into the casing 1.

In order to support the lamp in a vertical position, when the same is to be used as a pedestal lamp or lantern, a series of collapsible feet are provided and are preferably mounted with their operating means on the rear end cap 16, which is provided with a threaded portion 17 to engage the threaded portion 15 of the casing. Secured to a stud 20, which is pivoted in the center of the cap 16, is a plate or disk 19 to the inner face of which are secured arcuate legs 21 by means of pivot pins 22 mounted near the ends of the legs 21 and near the peripheral edge of the disk. Each of the legs 21 has an angularly disposed foot portion 23, which, when the legs are in folded position, occupy peripheral slots or notches 25 in the edge of the disk 19. Formed in the body of each of the legs 21 is an arcuate slot 24, which is engaged by a stud or pin fixed in the face of the cap 16, so that, when the disk 19 is given a partial rotation by means of the projecting head of the stud 20, the legs 21 will move either outwardly or inwardly, depending upon the direction of rotation, by the en-

gagement of the pins 26 with the slots 24. When the legs are moved outwardly, they afford a stable support for the lamp structure. When the legs are simultaneously 5 swung inwardly, by the partial rotation of the plate 19, the outer edges of the legs conform substantially to the peripheral edge of the disk, as shown in Fig. 3, and the angular flanges or projections 23 lie within the 10 notches 25.

What I claim is:

1. An electric lamp including a casing having lateral openings in its fore portion, a socketed support and reflector in said casing adjacent said openings, a lens carrying cap in threaded engagement with the front end of the casing, a sleeve slidable on the casing to cover and uncover the lateral openings, a rear end cap, and foldable feet carried by 20 said rear end cap to support the lamp.
2. An electric lamp including a casing having lateral openings in its fore portion, a socketed support and reflector in said casing adjacent said openings, a lens carrying cap in threaded engagement with the front end of the casing, a sleeve slidable on the casing to cover and uncover the lateral openings, a rear end cap, foldable feet carried by 30 said rear end cap to support the lamp, and means for operating said feet simultaneously.
3. An electric lamp including a casing having lateral openings in its fore portion, a socketed support and reflector in said casing adjacent said openings, a lens carrying cap in threaded engagement with the front end of the casing, a sleeve slidable on the casing to cover and uncover the lateral openings, a rear end cap, a rotary plate centrally 40 pivoted to said end cap, arcuate feet pivoted to said plate and having cam slots therein, and pins on said cap engaging the cam slots to swing the feet to spread and folded positions respectively when said plate is rotated.
4. An electric lamp including a casing having lateral openings in its fore portion, a socketed support and reflector in said casing adjacent said openings, a lens carrying 50 cap in threaded engagement with the front end of the casing, and a sleeve slidable on the casing to cover and uncover the lateral openings, said sleeve having a threaded end to engage the threads on the lens carrying 55 cap.

In testimony whereof I affix my signature.
SAMUEL H. NUCKOLLS.
